UNITED STATES PATENT OFFICE.

OSKAR LASCHE, OF CHARLOTTENBURG, GERMANY, ASSIGNOR TO GENERAL ELECTRIC COMPANY, A CORPORATION OF NEW YORK.

STEAM-TURBINE.

Specification of Letters Patent.

Patented Feb. 8, 1916.

1,171,216.

Application filed December 12, 1914. Serial No. 876,801.

To all whom it may concern:

Be it known that I, OSKAR LASCHE, a subject of the King of Saxony, residing at Charlottenburg, Germany, have invented 5 certain new and useful Improvements in Steam-Turbines, of which the following is a specification.

This invention relates to elastic fluid turbines, and its object is to remove the water 10 from steam in the low pressure stages of a steam driven turbine.

In the passage of the motive fluid through a multi-stage turbine, the gradual extraction of energy in the form of heat reduces 15 the steam to a state of saturation in the lower pressure stages, so that when it enters the last one or two bucket wheels its moisture content is frequently as high as ten per cent. The particles of water entrained by the steam due chiefly to their 20 relatively high velocity have a destructive action on the buckets in said stages.

It is found that the buckets of the low pressure wheels are worn principally at 25 the outer ends. This fact may be explained from the circumstance that the drops of water which form in the low pressure part of the turbine during the expansion of the steam are, by reason of their greater specific gravity, thrown outward by centrifugal force, so that the steam which leaves 30 the outer ends of the wheel buckets contains a greater amount of moisture than the steam leaving the inner ends of the buckets. The 35 steam flows through the nozzles in this same stratified condition, the wetter steam striking the outer ends of the buckets on the succeeding wheel, and thus causing greater wear at these points. The nozzles at the 40 lower side of the casing will be worn more than those at the top, because the wet heavier steam naturally gravitates to the bottom of the casing. An obvious way to overcome this difficulty would be to superheat the 45 steam at the outset to a degree which would cause it to flow through the entire machine in a dry condition. This, however, would require the initial superheat to be so great as to be impracticable. Another mode of 50 reaching the same result would be to subject the steam to an intermediate superheating operation. But in either case, the cost of the additional plant would, in a large majority of cases, be prohibitive.

55 By the present invention, the water of

condensation is taken out of the steam in the low pressure portion of the turbine by a simple mechanical device, comprising a cutting away of the outer sides of the nozzles to a point beyond the periphery of the 60 buckets to which said nozzles deliver steam, and also the provision of drain passages in the lower side of the wheel chambers in a horizontal turbine, through which the water can escape to the condenser or to any 65 other suitable receptacle.

The accompanying drawing is a longitudinal vertical section of the low pressure end of a horizontal turbine embodying my 70 invention.

The casing 1 is divided by diaphragms 2 into wheel chambers or stages in which the bucket wheels 3 revolve. Nozzles 4 are provided in the diaphragms, and those which deliver steam to the last two or three of the 75 low pressure wheels are so constructed that at their mouth they project slightly beyond the periphery of the wheel buckets. The nozzles may be cut away at their outer sides to effect this result as indicated at 5; 80 either entirely, or at intervals forming a plurality of grooves running lengthwise of the machine. Other equivalent means for effecting a separation of the water from the steam will readily suggest themselves to 85 the skilled engineer. In this way, the small outer and wetter stratum of the total jet of steam does not come in contact with the wheel buckets, but passes outside the periphery of the wheel, and collects in the 90 spaces or pockets 6 between the diaphragms; from which it may be drained off through passages 7, either to the exhaust conduit 8 leading to the condenser, or to any other 95 suitable receptacle.

In accordance with the provisions of the patent statutes, I have described the principle of operation of my invention, together with the apparatus which I now consider to represent the best embodiment thereof; 100 but I desire to have it understood that the apparatus shown is only illustrative, and that the invention can be carried out by other means.

What I claim as new and desire to secure by Letters Patent of the United States, 105 is:—

1. The combination with an elastic fluid turbine provided with bucket wheels and nozzles for directing the elastic fluid against 110

them, of means forming a passage in the nozzles which is beyond the periphery of the next succeeding bucket wheel so that fluid of condensation may escape past the periphery of such buckets.

2. An elastic fluid turbine having stage nozzles provided with means for directing water of condensation past the periphery of the succeeding bucket wheel.

10 3. An elastic fluid turbine having its low pressure stage nozzles cut away at their outer sides to permit water of condensation to escape past the periphery of the succeeding bucket wheel.

15 4. An elastic fluid turbine having its low pressure stage nozzles cut away at their outer sides to permit water of condensation to escape past the periphery of the succeed-

ing bucket wheel, and drain passages opening from the spaces between the diaphragms. 20

5. An elastic fluid turbine divided into stages, each stage having a fluid discharging device and a rotor means acted upon by the fluid from said device, the outer surface of the said device being at a greater 25 distance from the rotor axis than the ends of the rotor buckets coöperating therewith to permit condensation to be discharged beyond the path of said buckets.

In witness whereof, I have hereunto set 30
my hand this 5th day of November, 1914.

OSKAR LASCHE.
